UNITED STATES PATENT OFFICE.

AP TREVOR JONES, OF CHICAGO, ILLINOIS, ASSIGNOR TO AMERICAN STEEL
FOUNDRIES, OF CHICAGO, ILLINOIS, A CORPORATION OF NEW JERSEY.

ANCHOR ARRANGEMENT.

1,373,741.

Specification of Letters Patent.

Patented Apr. 5, 1921.

Application filed May 1, 1920. Serial No. 378,031.

To all whom it may concern:

Be it known that I, AP TREVOR JONES, a citizen of the United States, residing at Chicago, in the county of Cook and State of Illinois, have invented certain new and useful Improvements in Anchor Arrangements, of which the following is a specification.

This invention relates to anchor arrangements.

General speaking, there are two types of anchors, one known as the stock anchor, in which the shank of the anchor has no relative movement with respect to its crown or head, and the other one known as the stockless anchor, in which the shank has a relative movement with respect to its crown or head. It is to the latter type of anchor that my invention has particular application.

The main advantages of the stockless type of anchor over the other type are the ease of stowing away the anchor on the ship, and primarily in that the stockless type of anchor has two flukes for simultaneously engaging and hooking into the bottom of the sea for holding firmly.

The one disadvantage of the stockless anchor is that the flukes thereof are a little slow in hooking into the bottom of the sea after reaching same.

Accordingly, one object of this invention is to overcome this disadvantageous feature in a simple and efficient manner.

Another object is to provide a stockless anchor adapted to meet all of the requirements for successful use.

These and other objects are accomplished by means of the arrangement disclosed on the accompanying sheet of drawings, in which—

Figure 1 is a front elevation of an anchor embodying my invention;

Fig. 2 is a side elevation of the same anchor;

Fig. 3 is a fragmentary side elevation of the same anchor, a portion of the head being in section, and showing the shank in vertical position with the flukes at an angle of 45° with respect thereto, one of the two positions taken by the parts of the anchor as the anchor is being lowered and raised; and,

Fig. 4 is a side elevation of the same an-

chor, a portion of the head being shown in section, and showing the shank locked to the head of the anchor for causing a quick gripping action of the anchor when passed into engagement with the bottom of the sea, the position shown being that which is assumed after the head of the anchor has reached the bottom of the sea and the shank having moved downwardly a certain predetermined amount from its vertical position.

The various novel features of the invention will be apparent from the following description and drawings and will be particularly pointed out in the appended claims.

Referring to the figures of the drawings, it will be noted that I have shown a stockless type of anchor including a head 10 and a shank 11, the latter being pivotally connected to the former by means of trunnions 12 extending laterally from the shank and co-operating with bearing portions within the head. The inclined walls 13 of the head form stops for limiting the relative movement between the shank 11 and head 10. Preferably the maximum relative movement between said parts is about 90°, there being a 45° swinging movement to either side of a central aligned position of the head and shank. The head 10 is provided with two flukes 14 which are the ground engaging or gripping members. The head is also provided with oppositely and laterally extending projections 15 at the base of the flukes to cause the flukes to assume a digging or gripping position when the head of the anchor rests upon the bottom of the sea, as shown in Fig. 4. However, as mentioned hereinabove, the stockless type of anchor is a little slow in digging into and gripping the bottom of the sea in spite of the inclination given to the flukes by the projections 15, as shown in Fig. 4. To overcome this disadvantageous feature and to cause a quicker gripping action of the flukes of the anchor, I have provided means whereby the shank of the anchor will become locked with respect to the head thereof at the proper point so that the weight of the shank, together with the weight of at least a portion of the chain, will act in a manner to increase the dipping or gripping action of the flukes of the anchor.

As shown in Fig. 4 of the drawings, the shank 11 of the anchor is locked to the head 10 thereof by one of the two locking members 16. Said locking members are pivotally connected to the head of the anchor intermediate the shank and the flukes, and preferably as near the base of the shank as possible to occupy the minimum amount of space and to facilitate stowing away of the anchor.

10 To pivotally mount the locking members 16 in the head 10 of the anchor, said locking members 16 are provided with trunnions 17 which coöperate with suitable bearing portions carried by the head. Each of said locking members has a locking projection 18 which extends laterally inwardly from the main part of the locking member toward the shank to a point where said locking projections extend into the path of movement 20 of coöoperating locking lugs 19 carried on opposite sides of the shank 11. As shown in Fig. 4 of the drawings, one of the locking projections 18 is in locking engagement with one of the lugs 19 for holding the shank and head in a relative fixed position. With the parts as shown in this figure, the shank 11 is prevented from moving downwardly relatively to the head of the anchor, and accordingly, the weight of the shank, 30 and also the weight of the chain 20, or at least a portion thereof, and its clevis 21 connecting it to the shank 11 act in a manner to cause a relatively quick gripping or hooking action of the flukes into the bottom of the sea, this being especially true in view of the fact that the weight of the shank, clevis and chain act through a relatively long lever arm. These locking members 16 operate automatically to lock and unlock 40 the shank and head, and preferably are gravity actuated, having weighted portions 22 for causing the automatic locking and unlocking action. As shown in Fig. 3 of the drawings, it will be noted that the locking projection 18 is out of locking engagement with its associated locking lug 19 on the shank 11, the shank 11 being in a vertical position and the flukes arranged at an angle of 45° with respect thereto, this being 50 the position of the parts when the anchor is being lowered and raised.

Assuming that the anchor is being lowered, the head thereof finally reaches the bottom of the sea and gradually tips over 55 from the 45° angle to and beyond a horizontal position, as shown in Fig. 4. During this tipping action the locking member 16, which is to take effect, swings from an inoperative position into the operative locking 60 position at the critical point due to the weighted portion 22 of the locking member, causing the projecting portion 18 of the locking member to fall in front of the associated locking lug 19 on the shank for locking 65 the head and shank together for the

purpose hereinabove set forth. When the anchor is raised from the position shown in Fig. 4, the shank gradually moves toward a vertical position, as shown in Fig. 3, and at a critical point the locking projection 18 is caused to pull out of locking engagement with the locking lug 19 due to the action of the weighted portion 22 of the locking member for automatically causing the head and shank to be unlocked with respect to each other. The locking members 16 are prevented from moving progressively beyond a locking position by a tail portion 23 which engages a portion of the head. It will be understood that the locking and unlocking actions are as effective on one side as they are on the other.

It is my intention to cover all modifications of the invention falling within the spirit and scope of the following claims. 85

I claim:

1. A stockless anchor including a head, a shank movably connected thereto, and means carried by said head coöperating with said shank for locking said head and shank in a given relative position for creating a gripping leverage causing a quick gripping action of the anchor. 90

2. A stockless anchor including a head, a shank movably connected thereto, and means carried by said head coöperating with said shank for automatically locking said head and shank in a given relative position for creating a gripping leverage causing a quick gripping action of the anchor. 95

3. A stockless anchor including a head, a shank movably connected thereto, and gravity actuated means carried by said head coöperating with said shank for locking said head and shank in a given relative position for creating a gripping leverage causing a quick gripping action of the anchor. 100

4. A stockless anchor including a head, a shank movably connected thereto, and movably mounted members carried by said head and mounted upon opposite sides of said shank for coöperating with the latter to lock the head and shank in a given relative position for creating a gripping leverage causing a quick gripping action of the anchor. 110

5. A stockless anchor including a head, a shank movably connected thereto, and oppositely extending members carried by said head for engaging portions of said shank in given relative positions for creating a gripping leverage causing a quick gripping action of the anchor. 120

6. A stockless anchor including a head, a shank movably connected thereto and having locking lugs extending from opposite sides of said shank, and locking members carried by said head and movable into engagement with said locking lugs for locking said shank and head in given relative positions for creating a gripping leverage 130

causing a quick gripping action of the anchor.

7. A stockless anchor including a head, a shank movably connected thereto and having a projection thereon, and a member pivotally connected to the head of said anchor and having a portion for engaging said

shank projection for locking the head and shank in a given relative position for creating a gripping leverage causing a quick 10 gripping action of the anchor.

Signed at Chicago, Illinois, this 24th day of April, 1920.

AP TREVOR JONES.
